UNITED STATES PATENT OFFICE

173,100

TIMER

Eric P. Cahn, Brooklyn, and Nathan S. Stern,
Jackson Heights, N. Y.

Application October 5, 1953, Serial No. 27,078

Term of patent 3½ years

(Cl. D42—7)

To all whom it may concern:

Be it known that we, Eric P. Cahn, a citizen of the United States of America, residing at Brooklyn, county of Kings, New York, and Nathan S. Stern, a citizen of the United States of America, residing at Jackson Heights, county of Queens, Long Island, New York, have invented a new, original, and ornamental Design for a Timer, of which the following is a specification, reference being had to the accompanying drawing, forming a part thereof.

The single figure is a perspective view of a timer, showing our new design.

We claim:

The ornamental design for a timer, substantially as shown.
